(57) **CLAIM**

The ornamental design for a medical device adapter, as shown and described herein.

DESCRIPTION

FIG. 1 is a perspective view of a medical device adapter, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof.

The claimed medical device adapter is used to connect with various types of medical devices such as a screw driver, a tap, and etc.

1 Claim, 4 Drawing Sheets
